U.S. Appl. No. 29/699,564, filed Jul. 26, 219, Matthew Altschul.

Primary Examiner — Carla J Wright(74) *Attorney, Agent, or Firm* — Scheinberg & Associates, PC(57) **CLAIM**

We claim the ornamental design for a pocket case for a mobile communications device, as shown and described.

DESCRIPTION

FIG. 1 is a front, left-side and top perspective view of a pocket case for a mobile communications device according to the present design;

FIG. 2 is a back, right side, and bottom perspective view thereof;

FIG. 3 is a back elevation view thereof;

FIG. 4 is a front elevation view thereof;

FIG. 5 is a left-side elevation view thereof;

FIG. 6 is a right-side elevation view thereof;

FIG. 7 is a top plan view thereof; and,

FIG. 8 is bottom plan view thereof.

The broken lines depicting portions of a mobile communications device represent environmental subject matter that forms no part of the claimed design. The broken line features on the side surfaces of the article represent portions of the pocket case for a mobile communications device that form no part of the claimed design.
